UNITED STATES PATENT OFFICE

OTTO E. SZEKELY AND RUSSELL H. JOHNSON, OF HOLLAND, MICHIGAN

IRONING MACHINE

Application filed July 9, 1927. Serial No. 204,532.

In ironing machines it has been customary heretofore to have a plurality of rollers, certain of which were heated, or to have a cool roller with a heated ironing shoe, whereby the rollers or shoe were either permanently positioned relative to each other, or manual means were supplied to move either the rollers or the shoe.

This invention relates to ironing machines 10 of the type in which the heat is furnished to the ironing shoe which is located in operative relation to the ironing roller.

The present invention has for its primary object to provide improved and automatic 15 means for moving the ironing shoe towards or away from the ironing roller.

Another object is to provide novel and improved means for operating the ironing machine.

20 Another object is to provide new and novel clutch mechanism for stopping and starting the machine and which will automatically control the movement of the ironing shoe.

A further object is to provide a tilting 25 board arranged adjacent the ironing roller for controlling the operation of the automatic means for moving the ironing shoe.

And another object is to provide an ironing machine which is simple and efficient in 30 operation, which can be readily and economically manufactured, and which can be adjusted vertically on its frame work to suit varying conditions.

The accompanying drawings illustrate a 35 selected embodiment of the invention and the views are as follows:

Fig. 1 is an end view partly in section of the ironing machine.

Fig. 2 is a detail plan view of one end of 40 the machine.

Fig. 3 is a vertical detail sectional view of the machine taken on the line 3—3 of Fig. 5.

Fig. 4 is a detail longitudinal sectional view 45 on an enlarged scale.

Fig. 5 is a detail sectional view of the ironing machine showing some of the operating mechanism.

Fig. 6 is a detail view of the clutch oper- 50 ating mechanism.

Fig. 7 is a rear elevation.

Fig. 8 is a detail front elevation.

Fig. 9 is a plan view of the throwout disk.

Fig. 10 is a detail elevational view with parts broken away showing a portion of the device disclosed in Fig. 1 in another operative position.

Referring to the drawings 1 designates a suitable frame upon which a support 2 is integrally attached for supporting a motor 3. A worm 5 suitably supported in the frame 1 receives its power through the flexible connection 4 connected to the motor shaft. The worm wheel 6 mounted on a stub shaft 7 meshes with the worm 5. A spur gear 8 is integrally connected with the worm wheel 6 and receives its motion therewith.

The spur gear 8 is provided with clutch teeth 9 which are adapted to be engaged with the clutch member 10 arranged on the flat portion 11 of the shaft 7. A disk 12 is fixedly secured to the outer end of the shaft 7 and adapted to rotate therewith for a purpose to be later described.

A longitudinal shaft 13 extending entirely across the machine has a spur gear 14 loosely mounted thereon which meshes with the spur gear 8 and is adapted to be revolved thereby. This spur gear 14 has teeth 15 formed on the outer edge thereof which are adapted to be engaged by a clutch 16 arranged on the flat portion 17 of the shaft 13. A spring 18 surrounds the shaft 13 at the outer end thereof to normally cause the clutch 16 to be engaged with the teeth 15 on the spur gear 14. A suitable collar 19 is arranged on the end of the shaft and holds the spring 18 in normal position on the shaft 13.

A pivot shaft 20 suitably mounted in the casing 21 of the frame carries shifting yokes 22 and 23. The upper shifting yoke 22 is loosely mounted on the pivot shaft 20 and is adapted to operate the clutch 16, while the lower shifting yoke 23 is fixed to the pivot shaft 20 and is adapted to move therewith to operate the clutch member 10. Each of these yokes is provided with yoke pins 24 which engage the respective clutches to move the same in and out. A spring 25 has

55

65

70

75

80

85

90

95

100

the upper end thereof connected to a lug 26 formed on the casing 21 and the lower end connected to a lug 27 integrally formed on the yoke 23, and its purpose is to keep the 5 clutch member 10 normally out of engagement with the teeth 9 on the spur gear 8.

The upper yoke 22 has a button 28 fixed to the lower end thereof which is adapted to be engaged by the button 29 attached on the 10 inside of the disk 12. The lower yoke 23 has a button 30 which is adapted to engage one of the recesses 31 and 32 in the disk 12.

In Fig. 4 the button 29 is not in contact with the button 28 on the top yoke and therefore the 15 clutch 16 is in engagement with the spur gear 14, being held there by a spring 18 acting on the clutch 16. In Fig. 5, through rotation of the disk 12, the button 29 is in contact with the button 28 and therefore the 20 clutch 16 is out of engagement with the spur gear 14. When the buttons 28 and 29 are in contact with each other, the button 30 on the yoke 23 engages one of the recesses in the disk 12 as shown in Fig. 5. When the disk 12 is 25 in the position shown in Fig. 4 the button 30 may engage the recess 31 due to the action of the spring 25 on the yoke 23 normally holding the clutch out of engagement.

Suitable flanged supporting journals 33 are 30 fixed to the main shaft 13 at intervals and are adapted to receive the sheet metal casing 34 to which the packing 34' is secured and constitutes the ironing roller 35.

A tilting board 36 is supported by suitable 35 brackets 37 which are pivoted on the frame 1 at 38. A link 39 has one end secured to a lug 40 on the bracket 37 and the other end secured to an arm 41 connected to the pivot shaft 20.

40 Referring to Fig. 5 in which the clutches 10 and 16 are shown out of engagement, and assuming that the motor is running, the worm gear 5 will revolve the worm gear 6 and the spur gear 8 which are mounted 45 loosely on the shaft 7 and these in turn will revolve the spur gear 14 mounted loosely on the shaft 13, the balance of the mechanism will remain idle. When it is desired to operate the machine pressure is applied on the 50 outer edge of the tilting board 36 which will raise the inner edge thereof and cause the link 39 to move upwardly and, through the connection 41, rotate the shaft 20 in a small arc. The yoke 23 being fixed to the shaft 20 55 will move with this shaft and cause the pin 30 to leave its recess in the disk 12 and throw the clutch 10 into engagement with the teeth on the spur gear locking the same together. In this position the gears 6 and 8, stub shaft 60 7, clutch 10 and disk 12 are rotating in unison being directly driven by the worm 5.

65 After the disk 12 has moved 180 degrees, the button 30 which has been in contact with the ridge 32' will drop into the recess 31, Fig. 4, thereby throwing the clutch 10 out of

engagement with the teeth 9 on the spur gear 8. When the disk has moved through a small arc the button 29 will be moved away from the button 28 and permit the clutch 15 to engage the teeth 16 on the gear 14 for driving the main shaft 13 and the ironing roll 35.

70 When it is desired to stop the machine pressure is again applied to the outer edge of the tilting board which again causes the shaft 20 to rotate in a small arc, throwing the clutch member 10 in engagement thus rotating the stub shaft 7 which, in turn, rotates the disk 12 until the button 29 contacts with the button 28 to throw the clutch 15 out of engagement with the gear 14, thereby causing the shaft 13 and roller 35 to become stationary. Simultaneously with the contact of these two buttons 28, 29, the button 30 will engage the recess 32 on the disk 12 and cause disengagement of the clutch 10 from the teeth on the spur gear 8. The parts will then be in the position shown in Fig. 5.

75 A crank 43 is fixed to the stub shaft 7 and drives a crank arm 44 which is pivoted to a pin 45. Toggle arms 46 and 47 are pivoted at one end thereof to the pin 45 and have their other ends fixed to a rod 48 which is free to pivot in the frame.

80 An arm 49 interposed between the bifurcated end 50 of the toggle arm 47 is slidably mounted in a block 51 which is pinned between the bifurcated arm 52 pivoted on the cross rod 53. The arm 49 is threaded near its upper end to receive a wing nut 54. A 85 spring 55 is arranged between the wing nut and the block to form a flexible connection for driving the arm 52. A stop collar 55' is arranged on the outer end of the arm 49 to keep the same from sliding out of the block and for the purpose of returning the arm 52 to operating position. This arrangement of parts causes a reciprocatory movement of the arm 52.

90 Another arm 56 is pivoted at its lower end to the rod 53 and pivotally connected at its upper end to a lug 54 on the ironing shoe 57. This latter arm extends between the forked ends 58 of the arm 52. Each of these arms is slotted as at 59 to receive a key 60 which is pivoted to a cross shaft 61 passing through 95 bosses cast integral with the arm 56. A spring 62 has one end fastened to the tail piece 63 of the key and the other end fastened to the arm at 64. The purpose of this spring is to hold the key within the slots.

100 From the mechanism just explained pressure on the tilting board 36 will cause rotation of the stub shaft 7 and through the toggle mechanism cause the ironing shoe 57 to be automatically moved against or away from the ironing roller depending upon the position of the disc 12 and the clutches 10 and 16.

105 110 115 120 125 130 In case of emergency it may be desirable to move the ironing shoe away from the roller

by hand so a rod 65 fastened to the ironing shoe and the key 60 may be provided. By moving the rod 65 outward the key is released from the slots 59 and the shoe is free to move 5 away from the roller without interfering in any way with any of the toggle mechanism. This arrangement also permits the toggle mechanism to operate without affecting the shoe should pressure be accidentally applied 10 to the tilting board or should some of the parts jamb or otherwise not function. When the rod is moved forward the key again engages the slots and parts are again in position to be operated by the toggle mechanism.

15 A suitable handle or ball 66 may be fixed to the rod for actuating the same.

The ironing shoe is hollow and contains suitable heating means (not shown) required for heating the ironing shoe. This heating 20 means is supplied to the ironing shoe by means of a line 67 connected to the side thereof as shown in Fig. 1. This line may be either a gas line or an electric conduit depending upon the means employed for 25 heating the ironing shoe.

The frame 1 is provided with socket members 68 to receive tapered legs 69. The legs may be braced near the bottom by means of corner castings 70 and cross pipes 71 as shown. 30 Extension pipes 72 may be provided for adjusting the working height of the machine to meet varying conditions. This construction is free from the driving mechanism and permits the machine to be set up on its own 35 framework or the legs may be detached and the machine set on a table or bench.

In Fig. 1 the machine is shown in normal position, which is the ironing position. The operator feeds in the article to be ironed 40 at the right side of the machine, Fig. 1.

When it is desired to move the ironing shoe away from the roller it may be done by hand, as previously described, or it may be done automatically. If automatically, the 45 operator presses down on the outer edge of the tilting board 36 which revolves the pivot shaft 20 through the connecting link 39, thereby causing the yoke 22 to engage the clutch 10 with the teeth 9 on the spur gear 8. This 50 transmits motion to the stub shaft 7 which

revolves the disk 12 causing the pin 29 to engage the pin 28 and throw out the clutch 16 from the teeth 15 on the large spur gear 14, leaving the main shaft idle and roller at rest.

55 During this operation the button 30 will engage the recess in the disk 12 and cause the clutch 10 to become disengaged from the spur gear 8 thus leaving the machine idle.

While the stub shaft 7 is being rotated motion 60 is transmitted through the crank 43 and the crank arm 44 to the toggle mechanism and causes the arms 52 and 56 to pull the ironing shoe away from the ironing roller and the machine is at rest. To put the machine in 65 operation again all that is necessary is to

bear down momentarily on the outer edge of the tilting board 36 which again causes the stub shaft to rotate and the disk 12 returns to normal position. This motion of the disk causes the clutch 10 to become disengaged 70 from the spur gear 8 and allows the clutch 16 to become engaged with the large spur gear 14 on the main shaft, thus revolving the ironing roller. At the same time, and by the rotation of the stub shaft 7, motion is again transmitted through the crank 43 and crank arm 44 and through the arms 52 and 56 and the shoe is swung to normal position shown in Fig. 1. The stub shaft having rotated 180° 75 comes to rest and the shoe remains in operation relative to the roller.

Changes may be made in the form, construction and arrangement of the invention as set forth in the selected embodiment herein, without departing from the invention or 80 sacrificing any of its material advantages, and the right is hereby reserved to make all such changes as fairly fall within the scope 85 of the following claims.

I claim:

1. An ironing machine comprising a frame, a roller shaft mounted in said frame, an ironing roller on said shaft, a driven worm shaft, a stub shaft, a worm gear loosely mounted on said stub shaft and rotated by 90 said worm shaft, a spur gear connected to said worm gear, a large spur gear loosely mounted on said roller shaft and adapted to be operated by said spur gear, a clutch arranged on said roller shaft, means for normally causing said clutch to engage said 95 large spur gear for revolving the roller shaft, a clutch on said stub shaft and adapted for engagement with said first named spur gear to rotate said stub shaft, a tilting table, an ironing shoe, toggle mechanism connected to 100 said shoe and said stub shaft, means controlled by said tilting table and operated by a disk on said stub shaft for causing said toggle mechanism to move said shoe towards 105 or away from said ironing roller, and means actuated by said disk on the stub shaft for disengaging the clutch from the large spur gear when the shoe is moved away from the 110 roller.

2. An ironing machine comprising a frame, a roller shaft mounted in said frame, an ironing roller on said shaft, a driven worm shaft, a stub shaft, a worm gear loosely mounted on said stub shaft and rotated by 115 said worm shaft, a spur gear connected to said worm gear, a large spur gear loosely mounted on said roller shaft and adapted to be operated by said spur gear, a clutch arranged on said roller shaft, means for normally causing said clutch to engage said 120 large spur gear to revolve the roller shaft, a clutch on said stub shaft and adapted for engagement with said first named spur gear to rotate said stub shaft, a pivot shaft, yokes 125

130

arranged on said pivot shaft, a disk fixed to said stub shaft, an ironing shoe, a tilting table, toggle mechanism connected to the ironing shoe and the stub shaft and operated thereby, and means connecting the tilting table and the pivot shaft whereby movement of said table moves said pivot shaft and causes said disk to operate the clutches for operating or stopping the rotation of the roller shaft and for causing the toggle mechanism to move the shoe towards or away from the ironing roller.

3. An ironing machine comprising a frame, a roller shaft mounted in said frame, 15 an ironing roller on said shaft, a driven worm shaft, a stub shaft, a worm gear loosely mounted on said stub shaft and rotated by said worm shaft, a spur gear connected to said worm gear, a large spur gear loosely 20 mounted on said roller shaft and adapted to be operated by said spur gear, a clutch arranged on said roller shaft, means for normally causing said clutch to engage said large spur gear to revolve the roller shaft, a clutch 25 on said stub shaft and adapted for engagement with said first named spur gear to rotate said stub shaft, a pivot shaft, a yoke connected to said pivot shaft for operating said stub shaft clutch, a disk fixed to said stub 30 shaft, an ironing shoe, a tilting table, toggle mechanism connected to the ironing shoe and the stub shaft and operated thereby, means connecting the tilting table and pivot shaft to operate said pivot shaft, and a yoke loose 35 on the pivot shaft and operated by said disk for controlling said roller shaft clutch.

4. The combination with an ironing machine having a frame and an ironing shoe, of toggle mechanism for controlling the 40 operation of the shoe, an arm pivotally connected to said toggle mechanism and to the frame and having a bifurcated and slotted top, a cross shaft fixed to said frame, a second arm having a slot therein and arranged 45 between the bifurcated ends of said first arm and pivoted to said shoe and to said first named arm, a key pivotally mounted on said cross shaft and adapted to be received in the slots in both of said arms, and a spring for 50 normally holding said key in said slots and means for releasing said key.

5. The combination with an ironing machine having a frame and an ironing shoe, of toggle mechanism for operating the shoe, 55 an arm pivotally connected to the frame and said toggle mechanism and having a bifurcated slotted top, a cross shaft fixed to said frame, a second arm having a slot therein and pivoted to said shoe and said arm and arranged between the bifurcated ends of said first arm, a key pivotally mounted on said cross shaft and adapted to be received in the slots in both of said arms, a spring for normally holding said key in said slots and 65 means for releasing said key, a rod connected

to said key and said means whereby movement of said rod disengages the key from the slots and allows for manual movement of the shoe either towards or away from the ironing roller.

6. The combination with an ironing machine having a frame and an ironing shoe, of toggle mechanism for operating the shoe, an arm pivotally connected to the frame and to said toggle mechanism and having a bifurcated slotted top, resilient means for moving said arm, a cross shaft fixed to said frame, a second arm having a slot therein pivoted to said shoe and said arm and arranged between the bifurcated ends of said first arm, a key pivotally mounted on said cross shaft and adapted to be received in the slots in both of said arms, a spring for normally holding said key in said slots, and a rod connected to said key whereby movement of said rod disengages the key from the slots and allows manual movement of the shoe towards or away from the ironing rollers without affecting the operation of the resilient means.
